Term of patent 14 years

Int. Cl. D17—01

U.S. Cl. D56—9

FIG. 1

FIG. 2**FIG. 3**

FIG. 1 is a front, top and right side perspective view of a piano showing our new design;

FIG. 2 is a front elevational view; and

FIG. 3 is a right side elevational view.

The side of the piano not shown is a mirror image of the side shown. The back of the piano is conventional. The decorative panels on the upper front board, partially obscured by the music desk, are similar to the decorative panel on the lower front board. Each of the decorative panels of the upper front board extends approximately one-third the length of the upper front board, the remainder of the upper front board behind the music desk being plain and unornamented.

We claim:

The ornamental design for a piano, substantially as shown and described.
